UNITED STATES PATENT OFFICE.

BERNARD HAUSHEER, OF NORWICH, NEW YORK, ASSIGNOR TO BORDEN'S CONDENSED MILK COMPANY, OF NEW YORK, N. Y., A CORPORATION OF NEW JERSEY.

CAN-FILLING MACHINE.

1,012,545.

Specification of Letters Patent. Patented Dec. 19, 1911.

Application filed May 28, 1909. Serial No. 499,914.

To all whom it may concern:

Be it known that I, BERNARD HAUSHEER, a citizen of the United States, and a resident of Norwich, in the county of Chenango and State of New York, have invented certain new and useful Improvements in Can-Filling Machines, of which the following is a specification, reference being had to the accompanying drawings; in which —

10 Figure 1 is a front elevation of the filling machine, the runways for the cans being shown in section; Fig. 2 is a side elevation looking from the left in Fig. 1, and showing duct in section; Fig. 3 is a similar view, 15 looking from the right in Fig. 1; Fig. 4 is a sectional top plan view of the machine, the section being taken on a line *a—a* in Fig. 1; Fig. 5 is a sectional top plan view showing the can raising and gripping, or 20 alining, devices of one half of the machine, the section being taken on a line *b—b* in Fig. 1; Fig. 6 is a vertical sectional view taken on a line *c—c* in Fig. 1, looking from the left; Fig. 7 is an enlarged vertical 25 sectional detail view of the adjustable fastening devices for the reservoir and valve carrying plate; Fig. 8 is an enlarged vertical sectional detail view of one of the can filling cylinders which is adapted to receive, 30 and deliver the fluid for the cans, the controlling valve therefor and regulating sleeve being shown in section; Fig. 9 is a diagrammatic view showing a tray and cans about to be placed in position under the cylinders; 35 Fig. 10 is a similar view showing the tray and cans raised to bring the openings in the cans up to the nozzle of the fillers; Fig. 11 is a diagrammatic plan view showing the cans gripped at each side of the tray and 40 against the limiting stop; Fig. 12 is a diagrammatic view showing the tray and cans raised to the filling position, and means for raising same, and Fig. 13 is a diagrammatic view of the reservoir, and a portion of the 45 cylinders, showing the manner of collecting the surplus fluid after the cylinders have been filled.

My present invention relates to that class of machines whereby a plurality of alike 50 containers, as for instance, cans, used for liquid or semi-liquid products, as for instance, condensed milk, are simultaneously filled through openings in the ends, preliminarily to such openings being closed by her-

metically sealed caps. 77 Figs. 9, 10, 11, 12 55 indicates a type of said cans having such relatively small openings 77^a Figs. 10 and 11.

The objects of my present invention comprise improvements, in several particulars 60 hereinafter described, in construction and operation of such machines, as for instance in economy of manufacture, in preservation and economy of material handled, in 65 celerity and particularly in accuracy and precision of operation, whereby I am enabled to successfully fill the cans through openings of much smaller diameter than heretofore, with resulting economy of material and labor in sealing, and resulting advantage to goods from reduction of extent of seam to be hermetically sealed. I attain these and other advantageous objects by 70 my novel construction and devices as herein-after described and claimed.

75 Referring now to the drawings, my filling machine comprises two end-frames 1 and 2 and a central frame 3. These frames are stationary and support a thereto removably secured reservoir 4 having a substantially 80 horizontal bottom. To thus removably secure the reservoir 4 to the frames I prefer to use adjustable fasteners 5 comprising screw-threaded studs 6 held in each of the end-frames, nuts 7, and sleeves 8 (see Figs. 4 85 and 7). The reservoir is provided with feet 9, through which said studs pass (as shown in Fig. 7). The sleeve device enables me conveniently to raise or lower the reservoir when required by different conventional heights of cans. For instance, the reservoir being adjusted to suit a certain height of can, as shown in Fig. 7, to adapt 90 it to use on cans as much taller as the length of said sleeve, it is only necessary to screw 95 off the nuts 7, lift the sleeves, lift off the reservoir, then replace the sleeves, re-set the reservoir to rest on latter, and again screw down the nuts. By this means, without changing fastenings, I am enabled indefinitely 100 to regulate the height of the reservoir as desired by substitution of sleeves of appropriate length.

The reservoir has openings, and I provide means to feed milk through said openings 105 into the reservoir as follows: The front end of the reservoir 4 has secured proximately thereto an inclined feeding duct 10 having

its bottom lower and its top higher than said bottom of said reservoir. The flow through said feed duct is controlled or stopped, as may be required, by any convenient means, 5 as for example a gate-valve 11, located in the tube as shown. The construction of the valve itself is not shown as this will be readily understood. The liquid, or semi-liquid, material employed for filling, and to 10 which I shall hereafter refer for brevity as "the milk", is fed by gravity to the longitudinally extended feed duct 10 through a duct 12 (Fig. 1) from any desired source of supply, not shown.

15 By referring to Figs. 4 and 6, it will be seen that the duct 10 is provided with horizontally disposed longitudinally extended slots communicating lengthwise with the interior of said reservoir, through which slots 20 disposed in horizontal alinement with each other the milk passes from said feed duct into said reservoir; also that the said slots open into the reservoir closely adjacent to bottom of latter. The said conformation 25 and location of said slots is very important for the reason that thereby is insured a quiet and equable flow of milk into the reservoir, thus avoiding the heretofore highly undesirable disturbance and incorporation 30 into the milk of air resulting in frothing, etc. It will be observed that the said form and disposition of my slots between the duct and the reservoir insure in operation the introduction of additional milk below the 35 upper surface of the then contents of said reservoir.

The rear end of the reservoir 4 is preferably provided with a longitudinally extended well 14 (Figs. 4 and 6) having preferably a concavely curved bottom as shown. 40 This well is normally occupied by a movable member 15 having its bottom, as shown, preferably convexly curved. The member 15 is, as shown, entirely inclosed so as not 45 to act as a dipper or scoop for the milk. Said member is thus normally in the reservoir, or its well, and also in the milk when fed thereinto to a level above the inlets of the filling cylinders as hereinafter 50 described. The bulk of said member is such that its liquid displacement exceeds the bulk of milk located at any time above said inlets. From this it follows that when the member is raised out of the liquid the latter 55 flows into the space previously occupied by said member and the level of the milk is thus quietly lowered to below the level of said inlets. At one side said member 15 has 60 pivotal connection 15^a (Fig. 6) with a stationary part of said machine. Another part of said member 15 is, as at 15^b (Fig. 6), operatively connected with the shaft of the machine, whereby the said member may, when desired, be raised out of the milk for 65 the purpose hereinafter described. The

reservoir 4 is provided with a plurality of like operative devices, viz: in this instance can-filling members or cylinders 16, one of which I provide with a transparent portion enabling its interior to be viewed from the outside, as, for instance, I construct one of the said cylinders, indicated by 17 in Fig. 1, of glass. Each of said cylinders is provided with an inlet above, and an outlet below the bottom of said reservoir. Each cylinder terminates in a tapered bottom portion, or spout, 18 provided with an outlet or duct 19 terminating in the aforesaid nozzle portion 20. It will be observed that above said nozzle the spout is offset, forming an annular shoulder 20^a (Fig. 8). The cylinders 16, 17, are tightly secured to and supported by the normally stationary reservoir, forming in fact a part thereof. The nozzles 20 pass through a horizontally disposed plate 21 (Fig. 1) supported rigidly in said machine and provided with perforations, said perforations containing and closely fitting said nozzles and being predeterminedly located to insure exact register of said nozzles with the openings in the plurality of cans when latter are raised vertically toward said reservoir as hereinafter described. This plate 21 is of great importance, in fact indispensable to the securing of the precision and accuracy of operation required when, as is possible in my machine, cans with openings of smaller diameter than heretofore are filled. It will be observed that the nozzles 20 are of sufficient length to not only pass through the said plate 21, but also project somewhat below the same, so as to pass into the openings of the therewith registering and sub-located cans during filling. 100

To control the flow of liquid through the outlets 19 of the nozzles 20, I provide valves 22 (Fig. 8) preferably of compressible material, as for instance rubber, the said valves being carried by a stem 23, the upper end of which passes through and is supported by a plate 24 (Fig. 6). The stems 23 are loosely supported by the plate 24, admitting a certain amount of play in order that valve 22, which has a spherical end, may always 110 find its seat at outlet 19. This construction obviates necessity for perfect alinement of the openings in plate 21 with the outlets 19. To promote cleanliness and facility of cleaning I provide a sleeve 25 slidably mounted on stem 23, said sleeve contacting with said compressible valve 22, and having a recess, as shown at 25^a (Fig. 8), filled by a part of said compressible member. By this means I prevent milk from depositing 115 and remaining between the sleeve and the valve and greatly facilitate the required frequent cleanings of the parts. It may also be noted that the said sleeve 25 affords a means for gaging, with the utmost pre- 120

125

130

cision as is desirable, the contents of the cylinder, since the size of the sleeve may be varied as required to increase or diminish the capacity of the cylinder to the exact charge required for the cans. To keep the valves 22 firmly seated, I employ springs 27 (Fig. 6) which exert pressure upon adjustable collars 28, the upper ends of the stems 23 being provided with collars 29 to insure the lifting of the stems and valves as hereinafter described. The nozzles 20 together with their aforesaid therewith connected parts including said valves thus constitute broadly speaking a plurality of downwardly presented like operative devices having, as shown in the drawings, their centers equally spaced apart.

The plates 24 are secured to vertically movable end rods 30 and to the central rod 31 (Figs. 1, 2 and 3) by securing devices 32 (Fig. 1) the said devices being similar to the hereinbefore described securing devices 5. By referring to Figs. 1, 2, 3 and 6, it will be seen that the rods 30 and 31 are, by means 26 of links 33, connected to arms 34 (Figs. 1 and 6), which, at their outer ends, are swiveled on a rod 35 extending the length of the machine. The arms 34 carry a roller 36 which engages in cam slots 37 in disks 38, said disks being secured to and operated by the main shaft of the machine 39, which shaft, at its right hand end, as seen in Fig. 1, carries an operating lever 40, and at its left end a crank-arm 41. The crank-arm 41 is by link 43 connected to and operates an arm 42 (Fig. 2) which in turn operates the aforesaid gate-valve 11, not shown. The lower end of link 43 (Fig. 2) is slotted, as at 44, for a purpose hereinafter explained. A spring 45 returns the link 43 and thus the gate-valve 11 to normal position after each admission therethrough of a fresh charge of milk into the reservoir.

Shaft 39 carries adjacent to each end thereof, as shown in Figs. 1, 2 and 3, a face-cam 46, the cam of which is designed to operate an arm 47 also carried by rod 35, the said arms being adapted to operate arms 48 by means of links 49. The arms 48 are, by 50 means of links 50 at their outer ends, adapted to swing into and out of well 14 the aforesaid member 15. To the arms 48 are connected links 51, slotted as at 52 (Fig. 2), the said links being adapted to lift a stop or 55 movable gate, 53 (Fig. 6) disposed, when as normally closed, transversely of the path of the hereinafter described horizontal movement of the cans. A normally closed latch 54 supports said gate in its open position, said latch being provided with a projecting part 55 (Fig. 6), against which a projection 56 (Fig. 9), carried by rails 57 of the hereinafter described carriage of the machine, is adapted to strike to open said latch.

I provide means, in this instance a car-

riage, to simultaneously move the cans in a horizontal path below the said reservoir. The cans are provided with means to movably support a plurality thereof, as for instance a tray 78 (Figs. 10, 11 and 12). Said trays or containers for the plurality of cans adapted to be filled in one operation by my machine are constructed to loosely fit the group of cans, as shown, thus leaving room for alinement of the openings of latter by the devices hereinafter described. My said carriage comprises the said rails 57 and rods 58, which are slidably mounted in brackets as indicated by 59 (Fig. 1) carried by the end-frames 1 and 2. The said rails and rods are secured together at each end thereof by blocks 60, the said blocks being connected together, at the front of the machine only, by a bar 61. The bar 61 is provided with springs, or shock-absorbers, 62, whose function is to prevent jar on contact of the cans with bars 73, 74 and gate 53 when the cans are moved simultaneously in horizontal plane to below said reservoir 4. These springs, or shock-absorbers, are of great importance to the success of the alining operations hereinafter described.

Adjacent to the carriage of the machine I install runways, provided with rollers 63, to facilitate the horizontal movements of the cans. The runways are secured to bars 64 (Figs. 1 and 6) carried by the end frames 1 and 2 and by the central frame 3 as shown. I provide means to simultaneously move the said plurality of cans under treatment vertically toward and from said reservoir 4 and its therewith connected plurality of like-operative devices as follows:—Between the runways I place cross-bars 65, which pivotally support the tray lifters 66, connected by a spring 67. The free ends of the arms 47 carry a cross-bar 68 (Fig. 1) which in turn carries vertical pins 69, which, when the bar 68 is lifted, force the lifters 66 upwardly to raise the cans as stated. The blocks 60 of the carriage carry guard-bars 69^a (Figs. 1 and 5) to keep the tray or other container of the cans in alinement.

As contributing to accuracy and convenience in the movement of the carriage as a whole, I provide arms 70 pivoted at one end, as at 71 (Fig. 3), to the frame, and at the other end connected by a link 72 to block 60 of the carriage.

It is not only of the utmost importance, 120 in any event, that the openings of the plurality of cans simultaneously treated shall be, during their filling, brought directly under the nozzles, so as to insure no waste of milk, and consequently incomplete filling of 125 the cans from the predetermined charges contained in the cylinders, but it is also highly desirable that the openings in the cans shall be as small as possible since the smaller the openings, the less solder re- 130

quired to hermetically seal them, and the less extent of seam to be guarded against leaks and consequent infection. To this end I have provided special novel means where-
5 by is insured such precision and exactness of register by the centers of the nozzles with the centers of the openings that latter may be safely employed of much smaller diameter than heretofore and this without
10 impediment to the rapidity and perfection of the filling. Such means comprise the following devices for compelling the correct alinement, in all directions, of the units comprising the group or plurality of cans
15 simultaneously treated, thus insuring the requisite exactness of register between centers of openings and nozzles. The group of cans, its constituent units being of same proportions, size and location of openings, and
20 each of diameter equal to said space between centers of the nozzles, are set loosely, openings upward, upon some means adapted to movably support them, as for instance a tray as aforesaid, the construction of said
25 tray being such that, as shown, the cans project upwardly therefrom. When a machine of the type herein illustrated is used, it is preferable that the group should be of even number, as for instance 20 as shown
30 herein (Fig. 11). It will be understood that the position of the nozzles including the equal spacing apart of their centers has been predetermined and accurately and
35 rigidly located, as by help of plate 21, to serve said number after perfect corresponding alinement of its respective units.

The tray containing the cans as aforesaid is next placed in position on rollers 63 in front of the reservoir and within the carriage. The carriage is then pushed back toward the reservoir, which causes the springs 62 to bear against the tray and yieldingly impel it with its contained cans in a horizontal path toward the location re-
40 quired for filling, *i. e.* directly below the nozzles of the reservoir. Such progression of the carriage, and its contained tray and cans, results in projection 56, on carriage-rail 57, tripping latch 54, which releases
45 gate 53, which thereupon falls to its normal position transverse the path of said horizontal movement of the cans and contacts one side of the group when reached. It will be observed that the gate contacts with
50 and is opposed to the cans, as distinguished from the tray (see Fig. 10). At this stage the springs 62 are of especial value as shock-absorbers and relieve the cans from undesirable disturbance, though the carriage be
55 carelessly manipulated. Gate 53 thus moves some of the openings in the cans toward lineal alinement with some of the nozzles in a direction transverse that of the forward horizontal movement of the cans. As this
60 would be insufficient to secure required
65

register, I further provide novel means for insuring lateral alinement of the cans in directions parallel with that of their said horizontal forward progression. Such means are, in the present instance, my 70 lateral alining bars 74 and 73 disposed parallel to the path of said horizontal movement of the cans and disposed to crowd said cans transversely thereof and move some of their openings toward lineal alinement 75 with some of said nozzles.

Means are employed to movably and yieldingly support one of said alining bars each side of the cans. For instance, as shown in Fig. 1, the bars 73 are rotatably mounted on arms 73^a rotatable on pivots 73^b (Figs. 1 and 5) which enable said bars to swing or oscillate slightly without either unduly crowding or parting contact with the cans when latter are moved horizontally 85 and afterward vertically relatively to the nozzles. The yielding character of this grip may be increased by a spring 73^c in which case the arm is provided with a member 73^a through which a headed stem 73^d on 73^e 90 passes slidably, spring 73^c being interposed between the members as shown in Fig. 5. The bars 74 are preferably provided with adjusting screws 79 (Fig. 5) to adapt their position to the respective requirements of 95 different sizes of cans. The bars 74 are also provided with retracting springs 74^a causing them to bear equally at all times against screws 79 (Fig. 5). The bars 73 are further movable in that they are adapted to 100 rise simultaneously with the cans whereby their initial grip thereon remains undisturbed during the aforesaid movement. Means are provided to insure this upward movement of the bars 73, viz: the rod 68 is 105 connected with said bars by the brackets 80 and cross-bar 81 carried thereby so that the bars 73 rise and fall simultaneously with the rod 68 which raises the lifting-pins 69 which elevate the tray lifters 66 and 110 thus the cans. It will be observed that the alining bars 73, 74 are preferably disposed so as normally to project partly in the path of the said horizontal movement of the cans; in such case the ends of said bars facing the operator are beveled as shown in Fig. 11.

As the cans are moved horizontally toward their destined location beneath the nozzles they encounter the beveled ends of 115 the bars 73 and 74 which crowd them together, *i. e.* transversely of the path of their forward progression, thus moving some of their openings toward required lineal alinement. The capacity of the bars 73 to yield 120 under pressure from the cans prevents undue disturbance of the latter and gently and progressively brings them into the required order, the bar 74 being stationary at this stage affording a correct base for lateral 125 130

alinement like gate 53 for transverse alinement. When the limit of forward horizontal movement has been reached by the cans contacting with gate 53, the group will have 5 passed between and within the influence of the alining bars 73 and 74 and required alinement will have been nearly attained. It remains now to complete and perfect said alinement and this I accomplish by the 10 front or final alining bar 75, which extends along the front of the machine (Fig. 3) and is located and supported crosswise of the vertical path of the cans with such precision as to impart to the cans the finishing touch 15 required for their exact and complete aforesaid alinement with the centers of the super-supported operated devices. Bar 75 has, as will be seen, an inner downwardly beveled face. It is disposed partly in the path of 20 the upward movement of the cans to contact cans thereto adjacent during such movement and crowd them, and through them the remaining cans requiring it, toward said gate while between said lateral alining members 25 and thus bring the centers of the openings in the cans into final and exact register with the centers of the nozzles. It will be observed that during the said upward movement of the cans the transverse gate 30 53, the lateral alining bars 73 and 74 and the bar 75 all coact to hold and crowd the cans into the required position; also that during the horizontal movement of the cans the gate 53, the lateral bars 73 and 74 and 35 the shock-absorber springs 62 also similarly co-act.

By the means described I am enabled to automatically insure substantially exact register of the can openings with the nozzles 40 notwithstanding the machine is operated by substantially unskilled labor.

The construction of my said machine is such, owing to the movable character of gate 53 in combination with other adjuncts 45 described, that the filled cans are advantageously moved therethrough in the same direction of horizontal progression without the hitherto delaying necessity of returning them to the front of the machine. The 50 carriage is, as shown, adapted to the reception of two trays or groups of cans to be simultaneously filled. As soon as the forward one of these groups has passed within the control of the alining bars it is thereby 55 held sufficiently in required position. The carriage may then be retracted so as to insert in the front thereof another group of cans and its containing tray while the first group is being filled. The lifting of the 60 gate, as will be understood, enables the filled cans to be pushed out from under the nozzles to a point where they may be removed, and this is accomplished by the same forward movement of the carriage which brings 65 the next set of cans into control and grasp

of the alining devices for filling. Thus the cans progress intermittently through the machine in procession all in one direction which is a notable advantage and improvement in this art.

It will be understood that those portions of the machine shown in the drawings (Fig. 1) as located on the right of the frame 3 are substantially duplicates of the parts shown on the left side of said frame, and 70 that the drawings illustrate a construction adapted to fill simultaneously two groups of cans supported by two different trays.

The machine as shown is operated as follows:—The carriage is pulled out to the 80 position shown in Fig. 4. Two trays of cans are then placed upon the runways, one on each runway, as shown in Fig. 3, and as closely contacting as may be the respective guard-bars 69. The carriage is then 85 pushed inwardly toward the reservoir and its nozzles. When the carriage reaches the position shown in Fig. 9, the pin 56 pushes against and unlocks latch 54 as aforesaid, thus allowing the gate 53 to drop transverse the path of forward movement of the cans. While the cans are reaching this point the lateral alining bars 73 and 74 will have performed their functions as aforesaid. The lever 40 will then be forced toward the 90 right hand as shown in Fig. 3, whereby arm 41 will be raised to open the gate-valve 11, whereby the milk will be admitted into the reservoir. It will be noted that during this movement of the lever 40 no other movement will be imparted to any part of the mechanism. The gate valve is thus held 95 open until reservoir 4 is filled to about the dotted line in Fig. 6, as may be readily noted by the operator, that is to say until 100 the cylinders 16 and 17 are filled and the milk rises above them to about the location of said dotted line. After the reservoir has thus been sufficiently filled, lever 40 is reversed, *i. e.* pulled toward the left in Fig. 3, 110 until it has assumed its normal position as shown in that figure. This last mentioned movement closes the gate-valve. The next step is to move the cans vertically toward the nozzles until latter enter the can openings. This is accomplished by pulling the 115 lever 40 to the left of the position shown in Fig. 3 until the cams 46 have been rotated enough to cause the rollers 82 to rise on the eccentric portion 83, thus lifting arm 34, 120 bar 68, pins 69, tray-lifters 66, and so the cans, to the position shown in Fig. 10 relatively to the nozzles. Referring to Fig. 6 it will be noted that the concentricity of the 125 portion 84 of the cam 37 in disk 38 precludes movement by valves 21 during said raising of the cans. Simultaneously with said raising of the cans, arm 48 is moved up by link 49, whereby the member 15 is raised out of the milk (Fig. 13). The milk is thus 130

caused to flow quietly into the space previously occupied by the member 15 which owing to its displacement exceeding the bulk of the milk above the level of the inlets of the filling cylinders quietly lowers the level of the milk to below that of said inlets, leaving the latter exactly filled. Said raising of arm 48 simultaneously lifts gate 53 to normal position, whereby latch 54 again engages said gate as aforesaid. It will be perceived that when said gate falls, link 51 descends with it, causing upper end of slot 52 to engage pin 52^a on said arm 48. Consequently when latter is again raised, gate 53 is likewise. To cause the milk to flow into the cans, lever 40 is pulled still farther toward the left in Fig. 3, whereby portion 85 of cam slot 37 will, through action of rollers 36, arms 34, rods 30 and 31, and connecting links 33, lift plate 24, thus raising the therewith connected valves 22 from their seats on the nozzle outlets 19, thus permitting the milk to flow down through the nozzles and openings of the cans into the latter. After a group of cans has thus been filled, lever 40 is pushed back to its normal position, whereby the member 15 is returned into well 14, thereby expelling milk from latter and back into the reservoir to mix with the charge supplied to latter for the next group of cans. The curved conformations of well 14 and member 15 and the rotary movement of latter are of special advantage in that splashing or other undesirable agitation of the milk and resulting introduction thereto of air are thereby obviated.

It will be noted that means employed by me to movably support the plurality, or group, of cans, *i. e.* the tray 78 for instance, is designedly constructed so as to loosely hold the cans, that is to say the confining edge as at 78^a, Fig. 10, offsets by a considerable space the cans when latter are finally alined, such construction not only facilitating the charging of the cans but more particularly affording space for their movements during alinement, and thus insuring latter and resulting desirable register notwithstanding some inaccuracy in positioning of the tray itself.

It will also be noted that my said improvements are applicable not only to the cylindrical type of cans shown in the drawings, but also to cans of other forms, as for instance rectangular cans, and that I do not confine myself to the particular forms and proportions of parts, or to any of them as shown in my accompanying drawings; likewise that my said improvements are applicable not only to cans specifically but to groups of any other containers such as bottles for instance. Furthermore it will be obvious that my aforesaid alining devices can be utilized to center as aforesaid a plu-

rality of containers for other purposes, or operations, than filling, as for instance for cap placing, fluxing, crimping, soldering, or other operations in which a plurality of downwardly presented like operative devices are employed to impart simultaneous treatment to a plurality of cans.

Having thus described my invention, what I claim as new and desire to secure by Letters Patent is the following, viz:—

1. In a can-filling machine, a reservoir having a plurality of discharge nozzles communicating therewith, means to movably support a plurality of cans, a carriage to simultaneously move said cans in a horizontal plane below said reservoir, a movable gate, transverse the path of said horizontal movement, disposed to stop said cans under said nozzles, a normally closed latch to support said gate in open position, a projection from said carriage to open said latch, a rotatable shaft, and means operatively connecting said shaft with said gate to raise latter by rotation of said shaft.

2. In a can-filling machine, a reservoir having a plurality of discharge nozzles communicating therewith, means to movably support a plurality of cans, a carriage to simultaneously move said cans in a horizontal plane below said reservoir, and an alining bar having a beveled end yieldingly supported parallel with and partly in the path of said horizontal movement, disposed to crowd said cans transversely thereof and move them toward lineal alinement with said nozzles.

3. In a can-filling machine, a reservoir having a plurality of discharge nozzles communicating therewith, means to simultaneously move a plurality of cans in a horizontal plane below said reservoir, and an alining bar having a beveled end yieldingly supported parallel with and partly in the path of said horizontal movement, disposed to crowd said cans transversely thereof and move them toward lineal alinement with said nozzles.

4. In a can-filling machine, a reservoir having a plurality of discharge nozzles communicating therewith, means to movably support a plurality of cans, a carriage to simultaneously move said cans in a horizontal plane below said reservoir, an alining bar having a beveled end supported parallel with and partly in the path of said horizontal movement, disposed to crowd said cans transversely thereof and move them toward lineal alinement with said nozzles.

5. In a can-filling machine, a reservoir having a plurality of discharge nozzles communicating therewith, means to simultaneously move a plurality of cans in a horizontal plane below said reservoir, an alining bar having a beveled end supported parallel with and partly in the path of said hori-

zontal movement, disposed to crowd said cans transversely thereof and move them toward lineal alinement with said nozzles.

6. In a can-filling machine, a reservoir having a plurality of discharge nozzles communicating therewith, means to movably support a plurality of cans, a carriage to simultaneously move said cans in a horizontal plane below said reservoir, a movably and yieldingly supported alining bar parallel the path of said horizontal movement, disposed to crowd said cans transversely thereof and move them toward lineal alinement with said nozzles, means to move said cans vertically toward and from said reservoir, and means to simultaneously and proportionally raise and lower said alining bar.

7. In a can-filling machine, a reservoir having a plurality of discharge nozzles communicating therewith, means to simultaneously move a plurality of cans in a horizontal plane below said reservoir, a movably and yieldingly supported alining bar parallel the path of said horizontal movement, disposed to crowd said cans transversely thereof and move them toward lineal alinement with said nozzles, means to move said cans vertically toward and from said reservoir and means to simultaneously and proportionally raise and lower said alining bar.

8. In a can-filling machine, a reservoir having a plurality of discharge nozzles communicating therewith, means to movably support a plurality of cans, a carriage to simultaneously move said cans in a horizontal plane below said reservoir, an alining bar having a beveled end supported parallel with and partly in the path of said horizontal movement, disposed to crowd said cans transversely thereof and move them toward lineal alinement with said nozzles.

9. In a can-filling machine, a reservoir having a plurality of discharge nozzles communicating therewith, means to simultaneously move a plurality of cans in a horizontal plane below said reservoir, an alining bar having a beveled end supported parallel with and partly in the path of said horizontal movement, disposed to crowd said cans transversely thereof and move them toward lineal alinement with said nozzles.

10. In a can-filling machine, a reservoir having a plurality of discharge nozzles communicating therewith, means to movably support a plurality of cans, means to simultaneously move said cans vertically toward and from said reservoir, an alining bar disposed partly in the path of said vertical upward movement to crowd said cans into alinement with said nozzles during said movement.

11. In a can-filling machine, a reservoir having a plurality of discharge nozzles communicating therewith, means to simultane-

ously move a plurality of cans vertically toward and from said reservoir, an alining bar disposed partly in the path of said vertical upward movement to crowd said cans into alinement with said nozzles during said movement. 70

12. In a can-filling machine, a reservoir having a plurality of discharge nozzles communicating therewith, means to movably support a plurality of cans, means to simultaneously move said cans vertically toward and from said reservoir, an alining bar having a beveled face disposed partly in the path of said vertical upward movement to crowd said cans into alinement with 80 said nozzles during said movement.

13. In a can-filling machine, a reservoir having a plurality of discharge nozzles communicating therewith, means to simultaneously move a plurality of cans vertically toward and from said reservoir, an alining bar having a beveled face disposed partly in the path of said vertical upward movement to crowd said cans into alinement with 85 said nozzle during said movement.

14. In a can-filling machine, a reservoir having a plurality of discharge nozzles communicating therewith, means to movably support a plurality of cans, a carriage to simultaneously move said cans in a horizontal plane below said reservoir, a gate, transverse the path of said horizontal movement, disposed to stop said cans under said nozzles, alining members parallel the path of said horizontal movement disposed to 100 crowd said cans transversely thereof, means to move said cans vertically toward and from said reservoir, an alining bar disposed partly in the path of said vertical upward movement to crowd said cans into positions, 105 in which the center of each shall be in alinement with one of said nozzles.

15. In a can-filling machine, a reservoir having a plurality of discharge nozzles communicating therewith, means to simultaneously move a plurality of cans in a horizontal plane below said reservoir, alining members parallel the path of said horizontal movement disposed to crowd said cans transversely thereof, means to move said cans vertically toward and from said reservoir, an alining bar disposed partly in the path of said vertical upward movement to crowd said cans into positions in which the center of each shall be in alinement with one of 110 115 said nozzles.

16. In a can-filling machine, a reservoir having a plurality of discharge nozzles communicating therewith, means to movably support a plurality of cans, a carriage to simultaneously move said cans in a horizontal plane below said reservoir, a gate, transverse the path of said horizontal movement, disposed to stop said cans under said nozzles, a movably and yieldingly support-

alining bar parallel the path of said horizontal movement, disposed to crowd said cans transversely thereof toward lineal alinement with said nozzles, means to move 5 said cans vertically toward and from said reservoir, an alining bar having a beveled face disposed partly in the path of said vertical upward movement to crowd said cans into positions in which the center of each 10 is in register with the center of one of said nozzles.

17. In a can-filling machine, a reservoir having a plurality of discharge nozzles communicating therewith, means to simultaneously move a plurality of cans in a horizontal plane below said reservoir, a gate, transverse the path of said horizontal movement, disposed to stop said cans under said nozzles, a movably and yieldingly supported 15 alining bar parallel the path of said horizontal movement, disposed to crowd said cans transversely thereof toward lineal alinement with said nozzles, means to move said cans vertically toward and from said 20 reservoir, an alining bar having a beveled face disposed partly in the path of said vertical upward movement to crowd said cans into positions in which the center of each 25 is in register with the center of one of said nozzles.

18. In a machine of the class described, supported by normally stationary parts a plurality of downwardly presented like operative devices having their centers equally spaced apart, means to move simultaneously, in a horizontal path below said operative devices, a plurality of containers each of diameter equal to said space between said centers, and, connected with a stationary 35 part, a stop disposed transversely of said path to arrest progression of said containers when under said operative devices.

19. In a machine of the class described, supported by normally stationary parts a plurality of downwardly presented like operative devices having their centers equally spaced apart, means to move simultaneously, in a horizontal path below said operative devices, a plurality of containers each of 45 diameter equal to said space between said centers, connected with a stationary part a movable stop normally disposed transversely of said path to arrest progression of said containers when under said operative devices, and means to intermittently raise said 50 stop out of said path.

20. In a machine of the class described, supported by normally stationary parts a plurality of downwardly presented like operative devices having their centers equally spaced apart, means to move simultaneously, in a horizontal path below said operative devices, a plurality of containers each of diameter equal to said space between 60 said centers, connected with a stationary 65

part a stop disposed transversely of said path to arrest progression of said containers when under said operative devices, and connected with a stationary part, in advance of said stop, a laterally alining member disposed parallel with said path to crowd said containers transversely thereof toward positions in which the center of each will register with the center of one of said operative devices.

21. In a machine of the class described, supported by normally stationary parts a plurality of downwardly presented like operative devices having their centers equally spaced apart, means to move simultaneously, in a horizontal path below said operative devices, a plurality of containers each of diameter equal to said space between said centers, connected with a stationary part a stop disposed transversely of said path to arrest progression of said containers when under said operative devices, and connected with a stationary part, in advance of said stop, laterally alining members disposed parallel with said path to crowd said containers transversely thereof toward positions in which the center of each will register with the center of one of said operative devices.

22. In a machine of the class described, supported by normally stationary parts a plurality of downwardly presented like operative devices having their centers equally spaced apart, means to move simultaneously, in a horizontal path below said operative devices, a plurality of containers each of diameter equal to said space between said centers, connected with a stationary part a stop disposed transversely of said path to arrest progression of said containers when under said operative devices, connected with a stationary part, in advance of said stop, laterally alining member disposed parallel with said path to crowd said containers transversely thereof toward positions in which the center of each will register with the center of one of said operative devices, means to simultaneously move said cans in a vertical path when under said operative devices, and an alining member disposed cross-wise of said path to crowd said containers during vertical movement toward said stop, whereby the center of each said container is caused to register with the center of one of said operative devices.

23. In a machine of the class described, supported by normally stationary parts a plurality of downwardly presented like operative devices having their centers equally spaced apart, means to move simultaneously, in a horizontal path below said operative devices, a plurality of containers each of diameter equal to said space between said centers, connected with a stationary part a stop disposed transversely of said 130

- path to arrest progression of said containers when under said operative devices, connected with a stationary part, in advance of said stop, laterally alining members disposed each side of and parallel with said path to crowd said containers transversely thereof toward positions in which the center of each will register with the center of one of said operative devices, means to simultaneously move said cans in a vertical path when under said operative devices, and an alining member disposed cross-wise of said path to crowd said containers during vertical movement toward said stop, whereby the center of each said container is caused to register with the center of one of said operative devices.
24. The combination of a tray adapted to movably hold a plurality of like containers projecting upwardly therefrom, means to impart to said tray horizontal movement in a given direction, a movable gate normally supported and disposed in the path of said horizontal movement of said containers to arrest their progression relatively to that of said tray, means to intermittently lift said gate out of said path, alining members parallel said path disposed to crowd said containers transversely thereof, whereby said containers are automatically moved in said tray relatively thereto and to each other toward positions in which the center of each container will register with one of a group of predetermined points, substantially as and for the purposes described.
25. The combination of a tray adapted to movably hold a plurality of like containers projecting upwardly therefrom, means to impart to said tray horizontal movement in a given direction, a movable gate normally supported and disposed in the path of said horizontal movement of said containers to arrest their progression relatively to that of said tray, means to intermittently lift said gate out of said path, alining members parallel said path disposed to crowd said containers transversely thereof, whereby said containers are automatically moved in said tray relatively thereto and to each other toward positions in which the center of each container will register with one of a group of predetermined points, substantially as and for the purposes described.
26. The combination of a tray adapted to movably hold a plurality of like containers projecting upwardly therefrom, means to impart to said tray horizontal movement in a given direction, a movable gate normally supported and disposed in the path of said horizontal movement of said containers to arrest their progression relatively to that of said tray, means to intermittently lift said gate out of such path, alining members parallel said path disposed to crowd said containers transversely thereof, means to impart to said tray and containers vertical movement, an alining member disposed in parallelism with said gate above the path of said horizontal movement and one side the path of said vertical movement, whereby said containers are automatically moved in said tray relatively thereto and to each other until all have been crowded into positions in which the center of each registers with one of a group of predetermined points, substantially as and for the purposes described.
27. The combination of a tray adapted to movably hold a plurality of like containers projecting upwardly therefrom, means to impart to said tray horizontal movement in a given direction, a movable gate normally supported and disposed in the path of said horizontal movement of said containers to arrest their horizontal progression relatively to that of said tray, means to intermittently lift said gate out of such path, a movably and yieldingly supported alining member parallel said path disposed to contact with and crowd said containers transversely thereof, means to so support said alining member, means to impart to said tray and containers vertical movement, and an alining member disposed in parallelism with said gate above the path of said horizontal movement one side the path of said vertical movement, whereby said containers are automatically moved in said tray relatively thereto and to each other until all have been crowded into positions in which the center of each registers with one of a group of predetermined points, substantially as and for the purposes described.
28. In a can-filling machine, a reservoir having a can filling cylinder having a tapered bottom opening at its apex into a discharge nozzle, a valve stem vertically movable within said cylinder, a compressible valve member fitted to and carried by the lower end of said valve stem and adapted to close said nozzle, a sleeve slidably mounted on said valve stem above and contacting with said compressible member and having a recess filled by a part of said compressible member.
29. In a can-filling machine, a reservoir having extending downwardly therefrom and communicating therewith a plurality of can filling cylinders each provided with a discharge nozzle opening in substantially the same horizontal plane, means to movably support a plurality of cans provided with openings, means to aline said openings into register with said nozzles, means to simultaneously move said cans vertically toward and from said reservoir, a horizontally disposed plate supported rigidly in said machine and provided with perforations con-

taining and closely fitting said nozzles, and predeterminedly located to insure exact register of said nozzles with said openings in said cans when latter are raised vertically 5 toward said reservoir.

30. In a can-filling machine, a reservoir having a plurality of discharge nozzles communicating therewith, means to movably support a plurality of cans provided with 10 openings, means to simultaneously move said cans in a horizontal plane below said reservoir, means to simultaneously move said cans vertically toward said reservoir and means during the aforesaid movements to 15 move said cans horizontally relatively to each other until the centers of said openings register with the centers of said nozzles.

31. In a can-filling machine, a reservoir having a plurality of discharge nozzles communicating therewith, a tray adapted to 20 movably support a plurality of cans pro-

vided with openings, a carriage to move said tray in a horizontal plane below said reservoir, on one side of said carriage a movable gate, transverse the path of said horizontal movement, disposed to stop said cans under said nozzles, a spring interposed 25 between the opposite side of said carriage and said tray, alining bars parallel the path of said horizontal movement, disposed to 30 crowd said cans transversely thereof, means to simultaneously move said cans vertically under said reservoir, an alining bar disposed in the path of said vertical upward movement to crowd the said cans into positions 35 in which each of said openings registers with one of said nozzles.
